UNITED STATES PATENT OFFICE.

JAMES A. MITCHELL, OF DAYTON, OHIO.

DESIGN FOR A WIRE-TIGHTENER.

SPECIFICATION forming part of Design No. 29,630, dated November 8, 1898.

Application filed October 3, 1898. Serial No. 692,562. Term of patent 7 years.

To all whom it may concern:

Be it known that I, JAMES A. MITCHELL, a citizen of the United States, residing at Dayton, in the county of Montgomery and State 5 of Ohio, have invented and produced a new and original Design for Wire-Tighteners, of which the following is a specification, reference being had to the accompanying drawings, forming part thereof.

Figure 1 shows a front view, and Fig. 2 a back view, of my design. Fig. 3 shows an edge view of the same. To fully illustrate my design these three views are deemed necessary.

5 The leading feature of my design is the pe-

culiarly-notched double disk A B, having the peculiar ²⁰ shaped peripheral openings, as at C C, with a series of grooves D D and perforations E E on the front and back of the double disk.

Having described my invention, what I claim as new, and desire to secure by Letters Patent, is—

The design for a wire-tightener, as herein shown and described.

JAMES A. MITCHELL.
